UNITED STATES PATENT OFFICE.

ROBERT F. HUDSON, OF RICHMOND, VIRGINIA, ASSIGNOR TO WILLIAM J. FORD, TRUSTEE, OF FREDERICKSBURG, VIRGINIA.

TRAIN-CONTROL APPARATUS.

Application filed November 8, 1923. Serial No. 673,496.

To all whom it may concern:

Be it known that I, ROBERT F. HUDSON, a citizen of the United States, residing at Richmond, in the county of Henrico and 5 State of Virginia, have invented certain new and useful Improvements in Train-Control Apparatus, of which the following is a specification.

This invention relates to improvements in 10 train control apparatus, one object of the invention being the provision of a novel and practical arrangement of shoe, so arranged and mounted as to be brought into contact with the ramp rail only when approaching the same, the ramp rail being disposed adjacent to the traffic rail and slightly above the same and as particularly set forth in my U. S. Letters Patent No. 1,387,400, dated August 9th, 1921. 15 A further object of this invention is to provide a heavy wheel mounted so as to run at all times upon the traffic rail, but being of greater width than the tread of the rail so as to ride upon the ramp rail and out of 20 contact with the traffic rail, there being provided a swinging contact shoe, which is operated by the rise and fall of the traffic rail engaging wheel to bring the contact shoe into engagement with the ramp when 25 the traffic rail engaging wheel is in engagement with the ramp, or vice versa. 30

A still further object of the invention is the provision of a type of shoe and contact which is readily applied to any of the 35 ramp rail systems now in use, and which will permit the ramp to be placed in such a position as to be free of all clearance objections, and adaptable for use where a third rail for electricity is employed.

40 In the accompanying drawings:—

Figure 1 is a side elevation of a portion of traffic rail with the shoe and rail engaging wheel in normal position.

45 Figure 2 is a similar view showing the parts in the position they assume when engaging a ramp rail.

Figure 3 is a front elevation of the same as shown in Figure 1.

50 Figure 4 is a view illustrating the two ends of the ramp showing the wheel when on the traffic rail and also upon the ramp rail.

Figs. 5 and 6 are views of a modified form.

Referring to the drawings, the numeral 55 5 designates a support, which is adapted to be mounted upon a vehicle so that the traffic rail engaging wheel 10, will run upon said rail, and upon any part of the vehicle as may be decided upon as the best. This 60 frame 5 carries a supplemental frame 6 in which the cylindrical stem 7 of the wheel carrying yoke 8 is mounted for sliding movement, the axle 9 supporting the wheel 10. This wheel with its own weight and 65 the action of the spring 11, exerts a pressure of approximately 800 pounds upon the traffic rail 27.

The two studs 12, one carried by each 70 member of the yoke 8, fits in the elongated slot 13 of the swinging frame 14, fulcrumed between the lugs 15 by means of the pin 16, so that when the wheel 10 is held downwardly upon the traffic rail 27, the tubular casing 17 will be elevated. Mounted for 75 slight vertical movement with the casing 17, is the shaft 19, which carries upon it a spring 20 within the chamber 18 of the casing, so that the lower end 21 having the ramp rail engaging contact 23 removably 80 attached thereto by the bolt 22, will resiliently engage the ramp rail when the parts are caused to assume the position as shown in Figure 2, when wheel 10 rides upon the ramp rail 29 and is elevated upon the traffic rail. 85

A switch which constitutes part of a train control circuit the detail of which is not here set forth may be attached in any desired manner, but is here shown as the stationary contact 24, the movable member 25 and the plate 26, attached to be carried by the upper end of the stem 7.

The traffic rail 27 is mounted upon ties 28, and the ramp rail 29 preferably 95 designed for use in conjunction with this shoe apparatus is supported in castings or angle members 30.

From the foregoing description taken in connection with the drawings it is evident that with a shoe mechanism constructed as herein set forth that the present device may be used under all present clearances, as the wheel 10 and contact 23 will follow the wheels of the vehicle, and can be attached to the pilot of a locomotive, to the tender, or in fact at any point desired, and not project beyond the traffic rail to an objec- 100 105

tionable distance, thus rendering this device very easy of installation and positive and efficient in its workings.

In the form shown in Figures 5 and 6 brace members 34 are secured to appropriate points of the journal boxes J on each side of the wheel truck and support a beam 35 extending laterally across the end of the truck to form a rigid supplemental frame to carry 10 the contact wheel and scraping shoe assembly.

A bracket 36 is mounted on the beam, and a lever 37 is fulcrumed thereon at 38. In its free end is formed a casing 39 for the shaft 40 carrying the ramp scraping member 41 normally pressed down toward the rail by the spring member 42.

The other end of the lever is connected through a horizontal slot 44 in the lever and 20 through a vertical slot 45 in the bracket by a pin 46 to a yoke 47 which slides up and down in the bracket and carries a wheel 48 cut away at 49 to clear obstructions at the track side and to contact with the ramp 50.

25 A portion 51 of the wheel rides the traffic rail 52 in front of the truck wheel 54 and when a ramp is reached is lifted from the traffic rail by contact with the ramp rail. At the same time the contact scraper 41 is lowered to the ramp rail surface and held 30 against it by action of the spring 42 aforesaid on the free end of the lever 37 and by the spring 55 acting against the yoke 56 on the bracket 36 against the other end of the lever 37 through its pin 46 connection with the yoke 47.

Electric circuit contacts 57 and 58 and 59 are mounted to be opened or closed as the wheel 48 and yoke 47 raise and lower.

40 While in the foregoing I have described specific embodiments, and have mentioned only certain possible modifications, it will be appreciated that in practice I do not limit myself to such specific details as herein 45 set forth, but may resort to any practical modifications, falling within the scope of the appended claims.

What I claim as new is:—

1. The combination with a traffic rail and 50 a ramp rail disposed in parallel to and having its highest point slightly above the upper surface of the traffic rail, of a shoe mechanism including a vertically movable traffic rail engaging wheel slightly wider than the traffic rail and capable of engaging and being raised by the ramp rail, and a ramp rail contact operably connected to the first wheel whereby the contact is elevated when the wheel is upon the traffic rail and in 55 engagement with the ramp rail when the wheel is engaging the ramp rail.

60 2. A shoe mechanism including a frame, a

wheel mounted therein for vertical sliding movement, and ramp rail contact member 65 operably connected to the wheel whereby as the wheel is lowered the contact is elevated and vice versa.

3. A shoe mechanism including a frame, a yoke mounted therein for sliding movement, a wheel carried in said yoke, and a ramp 70 rail engaging contact carried by the frame and operably connected to the yoke, whereby when the yoke is held downwardly the contact is raised and vice versa.

4. A shoe mechanism including a frame, a sliding yoke mounted therein and normally pressed downwardly, a traffic rail engaging wheel carried by the yoke, and a ramp rail 75 engaging contact operably connected to the yoke and held upwardly when the wheel is in engagement with the traffic rail and vice versa.

5. A shoe mechanism including a frame, a sliding yoke mounted therein and normally pressed downwardly, a traffic rail engaging 80 wheel carried by the yoke and slightly wider than the traffic rail, said wheel when engaging a ramp rail being elevated out of contact with the traffic rail, and a ramp rail 85 engaging contact operably connected to the yoke, whereby when the wheel is in engagement with the traffic rail said contact is raised higher than the ramp rail and when the ramp rail is engaged by the wheel the contact is in engagement with the ramp 90 rail.

6. A shoe mechanism including a frame, a sliding yoke mounted therein and normally pressed downwardly, a traffic rail engaging wheel carried by the yoke, and a resilient 100 ramp rail engaging contact operably connected to the yoke and held upwardly when the wheel is in engagement with the traffic rail and vice versa.

7. A shoe mechanism including a frame, a 105 sliding yoke mounted therein and normally pressed downwardly, a traffic rail engaging wheel mounted in the yoke, a lever fulcrumed to the frame and having one end operably connected to the yoke, and a ramp 110 rail contact mounted in the free end of the lever and moved up and down by the yoke.

8. A shoe mechanism including a frame, a sliding yoke mounted therein and normally 115 pressed downwardly, a traffic rail engaging wheel mounted in the yoke, a lever fulcrumed to the frame and having one end operably connected to the yoke, a casing mounted in the free end of the lever, and a spring pressed ramp rail contact mounted in 120 the casing.

In testimony whereof I affix my signature.

ROBERT F. HUDSON.
